ELECTRICAL APPARATUS

John W. Dawson, Wilkinsburg, Pa., assignor to Westinghouse Electric & Manufacturing Company, East Pittsburgh, Pa., a corporation of Pennsylvania

Application January 6, 1933, Serial No. 650,419

13 Claims. (Cl. 171—119)

My invention relates to transformer tap-changing systems and has particular relation to systems employing vapor-arc or electronic conduction devices for changing the active number of turns in a transformer winding without interrupting the load current thereof.

In changing the circuit connections to transformer taps under load, as is required to meet the conditions in the power circuits connected to the transformer, switching means capable of operating in a current-carrying circuit are required. In all such tap-changing systems utilized in the past, with which I am familiar, these switching means have been contactor type switches or circuit breakers employing well-known mechanically separable contact members. My invention contemplates replacing the conventional contactor type of switch, in transformer tap-changing systems adapted to operate under load with controllable vapor-arc or other suitable electronic conduction devices.

In a copending application Serial No. 626,866, by Joseph Slepian and Leon R. Ludwig, filed July 30, 1932, and assigned to the Westinghouse Electric and Manufacturing Company, there is disclosed a form of vapor-arc electronic conduction device which operates with a stationary poorly conducting make-alive element, which device possesses controllable and other characteristics that make it particularly suitable for use in transformer tap-changing systems. Hence, in disclosing my invention, the electronic devices illustrated and described are of the above-referred to type. The tap-changing systems with which they are shown as forming a part are of the single-winding type. It will be apparent, however, as the description proceeds, that my invention may also be practiced with the use of other types of electronic conduction devices, having proper characteristics, and that the basic principles thereof are in no way restricted to single-winding tap-changing systems.

In the above-identified copending application the type of vapor-arc device disclosed employs a made-alive element which must be excited to initiate the current-conducting period of each half cycle. Consequently in the absence of the excitation of this element the device will function as a complete insulator. By combining two half-wave conducting devices or by using a double-ended construction in the two ends of which conduction is effected for alternate half-cycles, conduction during both half cycles of the alternating-current cycle may be effected, which conduction is controllable by the make-alive element circuit

which may be of low capacity. Hence, by connecting suitable switching means in this circuit, relatively large amounts of power may be interrupted or permitted to flow through the device, and the functions of a conventional type of contactor switch are thus effectively simulated. Since the voltage drop through a vapor-arc device of the type under consideration is relatively low and practically independent of current magnitude, the power losses set up therein are small, especially 10 when the controlled power circuits operate at the relatively high voltages at present encountered in transformer tap-changing applications.

When properly controlled, vapor-arc devices of the type under consideration are capable of allowing the active power circuit connection to be shifted from one winding tap to another during the zero current period in the alternating-current cycle, thereby simplifying the operation of tap changing apparatus adapted to operate under load. In the 20 past, the use of a tap bridging auto-transformer has been required in the single-winding tap-changing apparatus and, the double-winding apparatus employs duplicate windings in the main transformer. This last-named characteristic of 25 vapor-arc devices is found to make possible tap-changing systems possessing heretofore unknown flexibility characteristics, which, together with the simple control arrangements for the devices, make a tap-changing system utilizing them, highly 30 practical.

One object of my invention is to provide a tap-changing system capable of service in loaded circuits, in which all switching in the power circuits is effected by the use of controllable vapor-arc or 35 electronic conduction devices.

Another object of my invention is to provide a tap-changing system in which a shift from one tap to another may be completely effected when the load current passes through zero.

A further object of my invention is to provide a transformer tap-changing system capable of operating under load in which large blocks of power may be controlled by the actuation of low-capacity switching means.

An additional object of my invention is to provide a tap-changing system in which the flexibility characteristics are substantially broadened.

My invention, together with additional objects and advantages, will best be understood from the 50 following description of specific embodiments thereof, when taken in conjunction with the accompanying drawings, in which

Figure 1 is a diagram of apparatus and circuits illustrating controllable vapor-arc conduction de- 55

vices arranged in a tap-changing system for a single-phase power transformer in accordance with my invention:

Fig. 2 is a diagram of voltage and current waves illustrating the characteristics of one of the full-wave conductive vapor-arc devices shown in Fig. 1;

Fig. 3 is a table setting forth the sequence of control operations required to effect changes in transformer tap connections in the system of Fig. 1;

Fig. 4 is a simplified representation of one of the vapor-arc devices of Fig. 1 illustrating certain additions to the make-alive element control circuits therefor;

Fig. 5 is a similar representation of one of the double-ended vapor-arc devices of Fig. 1 modified to have but a single make-alive element in each end of the device, which element may replace the two illustrated in Figs. 1 and 4;

Fig. 6 is a diagrammatic showing of two half-wave conducting vapor-arc devices interconnected in a manner to jointly effect full wave conduction;

Fig. 7 is a diagrammatic view of a tap-changing system which utilizes two full-wave conducting vapor-arc devices together with a plurality of transformer tap-selector switches of the conventional type;

Fig. 8 is a diagrammatic showing of apparatus and circuits illustrating an arrangement of control switches whereby a plurality of vapor-arc devices utilized in a tap-changing system of the type shown in Fig. 1 may be excited from but a single set of exciting transformers, and

Fig. 9 is a diagrammatic view of apparatus and circuits showing a single-winding tap-changing system utilizing a tap-bridging auto-transformer, in which vapor-arc devices have been substituted for the conventional contactor type of tap selecting switches.

Referring to the drawings, and particularly to Fig. 1 thereof, a power transformer 10 is shown as connected between alternating-current power circuit conductors 11 and load circuit conductors 12. The secondary winding 13 of the transformer is provided with tap connections 1 and 2, to which the load circuit 12 may be selectively connected through the controllable vapor-arc devices A and B respectively.

As shown, each of the devices A and B, which is capable of full-wave or symmetrical conduction, is of the double-ended type comprising an inverted U-shaped tube 14 of insulating material, such as glass, having pools 15 and 16 of mercury, or other vaporizable reconstructing material, disposed in the two ends thereof. In contact with each of the pools is disposed a pair of make-alive elements 18 and 19 of carborundum crystal or other poorly conducting material, more completely described in the previously mentioned copending application Serial No. 626,866, in which application the general form of double-ended vapor-arc device shown in Fig. 1 is disclosed as being provided with but a single make-alive element in contact with each mercury pool.

In a second copending application Serial No. 653,456, by Charles F. Wagner, filed January 25, 1933, and assigned to the same assignee as this invention, there is shown and described an asymmetrically or half-wave conducting vapor-arc device provided with a plurality of make-alive elements, each of which is disposed to accommodate a separate controlling influence. It will be recognized that each of the symmetrically conducting

devices shown in Fig. 1 thus embodies the multiple make-alive element principle extended to vapor arc devices of the double-ended or symmetrically conducting type.

In a vapor-arc device of the above-described type, current conduction between the anode and cathode elements can take place only when the make-alive element associated with the cathode is made active to liberate ions from the cathode material. Consequently, until an energizing current is applied to the make-alive elements, each of the devices A and B shown in Fig. 1 will act as an insulator during both half cycles of alternating-current voltage, and even though the transformer 10 is energized the load circuit 12 will be disconnected therefrom.

By exciting the make-alive elements associated with one or the other of mercury pools 15 and 16 of devices A and B, it is possible to make either one of these two pools a cathode, the other pool operating as an anode without a cathode spot thereon. Thus the desired symmetrical conduction feature may be obtained by exciting a make-alive element in one end of the device during alternate half cycles of alternating-current voltage and a make-alive element in the other end of the device during the remaining half cycles.

To supply exciting currents to the inner make-alive elements 18 of devices A and B in the system of Fig. 1, exciting transformers 22 and 24 are provided, while transformers 26 and 28 are similarly associated with the outer make-alive elements 19 of the two devices named. As shown, each exciting transformer comprises a primary winding 30 and two secondary windings 31, each of which secondary windings is disposed to impress between a make-alive element and the associated mercury pool of the vapor-arc device an exciting voltage. A suitable resistor 33 is included in each make-alive element circuit for the purpose of limiting the current supplied thereto.

The primary windings of transformers 26 and 28 are disposed to be energized, through circuits which include switches a and c, respectively, by a voltage derived from the power-source circuit 11, either through an auxiliary secondary winding of power transformer 10 or through the medium of a direct connection with the circuit conductors as illustrated. The primary winding of exciting transformer 22 is arranged to be energized through a circuit, which includes a control switch d, by the voltage appearing between the major element pools 15 and 16 of vapor-arc device B, while transformer 24 may similarly derive its energization, through a circuit including a control switch b, from the voltage appearing between the major element pools of device A.

Upon a proper excitation of either pair of make-alive elements 18 or 19 of vapor arc device A or B, the device is caused to conduct between the two mercury pools thereof a power-circuit current which may be designated by I in Fig. 2, in which figure wave E represents the transformer voltage applied to the tap circuit which includes the device. As a result of this current I, there is set up in the device a small arc drop of the general character indicated by wave 35 of Fig. 2. This arc drop will be observed to be a function of the current, it being in phase therewith rather than with the voltage E, which is shown as leading the current by an angle alpha intended to be representative of a lagging power factor load. Inasmuch as a slight delay in conduction initiation at the start of each half cycle 75

is necessarily present, this arc-drop curve has the peaks illustrated at 36.

The manner of operating the tap-changing system of Fig. 1 will be more clearly understood by reference to the control-sequence table of Fig. 3. As there set forth, when it is desired to connect load circuit 12 to tap 1 of the power transformer 10, control switch *a* is closed. This connects exciting transformer 26 to power source conductors 11 and effects the excitation of outer make-alive elements 18 of vapor arc device A. As a result of this excitation, device A becomes a full-wave conductor, thereby causing the load circuit to be connected to transformer tap 1.

To shift the load circuit connection from tap 1 to tap 2, switch *b* is next closed to connect exciting transformer 24 across the major elements of device A. The arc drop through the device in its conductive state, being of but a relatively small magnitude, is insufficient to effect the active excitation of the inner make-alive elements 18 of vapor arc device B so that device B still retains its insulating characteristics.

Switch *a* is next opened and the excitation of make-alive elements 18 of device A is thereby removed. The device accordingly ceases to conduct current when the power current wave next passes through zero with the result that during the next succeeding half cycle the voltage across the device no longer follows wave 36 of Fig. 2 but starts to follow wave E. At an early point in the half cycle, this potential attains a magnitude which is sufficient to actively energize make-alive elements 18 of device B, and thereby render it conductive. Such excitation being repeated at the start of each succeeding half cycle, the device B will by this means be rendered conductive, thereby establishing the connection of load-circuit 12 with transformer tap 2.

To make the conduction of device B independent of the potential across device A, switch *c* is now closed causing exciting transformer 28 to be energized from power-source conductors 11. Outer make-alive elements 18 of device B are now made active to maintain the device conductive so that control switch *b* may now be opened to remove excitation from the inner make-alive elements 18.

The load circuit 12 now being supplied from transformer winding tap 2 through device B, to shift the connection from tap 2 back to tap 1, switch *d* is first closed to connect exciting transformer 22 across the major elements of device B. Switch *c* is then opened to remove the excitation from the make-alive elements 18 of device B which allows the potential across this device to build up sufficiently to excite make-alive elements 18 of device A. This excitation renders device A conductive. Switch *a* is then closed to effect the excitation of the outer make-alive elements 18 by the power-source voltage, whereupon switch *d* may be opened to deenergize exciting transformer 22.

To disconnect the load from the tap 1 it is only necessary to open switch *a*, while to similarly disconnect it from tap 2 an opening of switch *c* will suffice.

It will be understood that means other than those specifically illustrated, as being dependent upon device potential, for effecting the excitation of one vapor-arc device in response to the discontinuance of conductivity of another device may also be utilized in the tap-changing system of my invention. The important requirement, as typified by the illustrated means, is that when

the first device ceases to conduct current, a second device shall as a result be rendered conductive so that the desired shift of circuit connection without interruption of circuit current may thereby be effected. My invention, therefore, is intended to typify all types of excitation control means which fulfill the above requirement,—a feature of tap-changing system operation which, insofar as I am able to learn, is capable of attainment only through the utilization of controllable electronic or vapor-arc conduction devices in place of tap switches of the conventional or mechanical type.

As has been explained, the arc drop across the vapor-arc device when conductive is ordinarily insufficient to effect, in a system of the type shown in Fig. 1, excitation of a second vapor-arc device when the excitation transformer of the second device is energized by the potential drop across the first device. In certain instances, however, the peak 36 (Fig. 2) of the arc drop wave of the first device may reach such a magnitude as to effect active excitation of the second device unless precautionary measures are resorted to. The showing of Fig. 4 illustrates one such measure which may be utilized to overcome this difficulty. In the supply circuits of the make-alive elements 18 and 19 are disposed inductive impedances 40 in combination with capacitors 42 which act to delay the building up of the make-alive current at the start of each half-cycle. This delay serves to prevent the voltage peaks in the arc drop through one device from effecting active excitation of an associated device until after the first device is rendered completely non-conductive.

The symmetrically conducting vapor-arc devices thus far described have been provided with two make-alive elements in contact with each of the mercury pools. In certain instances it may be found that a single make-alive element may instead be substituted if the excitation circuits associated therewith are properly modified. In Fig. 5, a single make-alive element 44 in each end of the vapor-arc device A' replaces the two elements 18 and 19 shown in the devices of Figs. 1 and 4. Element 44 is influenced by two separate exciting potentials derived respectively from the secondary windings 31 of the exciting transformers 22 and 26, specially proportioned resistors or impedances 33 being included in each of the supply circuits for the purpose of preventing the two separate exciting potentials from interfering with each other. With such properly proportioned circuits the single make-alive element 44 may be made to perform the same functions as do the two make-alive elements 18 and 19 in the previously described vapor arc devices. The sensitivity, however, of the excitation system of Fig. 5 is not as high as that of the double make-alive element arrangement which, in general, will be found preferable. It will be apparent, however, that vapor-arc device A' of Fig. 5 and the special excitation circuits associated therewith may be utilized to replace device A or device B in the system of Fig. 1, should such be desired.

In Fig. 6 I have illustrated two half-wave or asymmetrical conducting vapor-arc devices 45 and 46 inter-connected in a manner to effect full-wave conduction. Each of the devices is provided with a cathode pool 48 of mercury or other vaporizable reconstructing material and an anode element 49 spaced thereabove, in addition to a pair of make-alive elements 18 and 19, all

of which are enclosed in a suitably sealed container 47. It will be observed that the anode element 49 of the device 46 is connected through conductor 50 with the cathode element 48 of device 45, while anode 49 of device 45 is similarly connected with cathode 48 of device 46, connections with the main power circuit to be controlled being made by means of conductors 53 and 54. Excitation of the make-alive elements of devices 45 and 46 may be effected in a manner which is identical with that already described in connection with Fig. 1. Hence, it will be apparent that the combination of Fig. 6 may replace either of the devices A and B in the system of Fig. 1.

15 The tap-changing system of my invention is not limited to combinations involving only two taps as it will be evident that the system of Fig. 1 may be extended to include larger numbers of taps merely by adding more vapor-arc devices and associated excitation means. However, when it is desired to provide for more than two taps with but two vapor-arc devices, the system shown in Fig. 7 in which a plurality of tap selector switches 57 to 61, inclusive, are incorporated between the devices A and B and the taps 1 to 5, inclusive, of the secondary winding of power transformer 10' may be utilized. Inasmuch as the excitation equipment for the make-alive elements 18 and 19 of vapor arc devices A and B may be identical with that which has already been described in connection with Fig. 1, no showing of this equipment has been made in Fig. 7.

30

In operation of the system of Fig. 7, connection of the load circuit 12 with tap 1 is effected by first closing tap-selector switch 57 and then exciting, from the power-source voltage, vapor-arc device A to render it conductive. Transfer of the load circuit connection from tap 1 to tap 2 is effected by closing tap-selector switch 58, setting up excitation circuits for vapor-arc device B responsive to the potential across device A, removing the excitation from device A which renders device B conductive and then transferring the excitation of device B to power-source influenced circuits.

55 Transfer of the load-circuit connection from tap 2 to tap 3 may similarly be effected by opening switch 57 closing switch 58, setting up excitation circuits for device A which are responsive to the potential across device B, removing the excitation from device B to render device A conductive and then transferring the excitation circuits of device A to power-source voltage energization.

It will be apparent that further shifts of power circuit connection among remaining taps of the transformer winding may be effected by a similar manipulation of the tap-selector switches associated therewith and alternately rendering the vapor-arc devices A and B conductive in proper order. Shifting the tap connections in the reverse or voltage decreasing direction will be seen to be effected by a modified manipulation of the tap selector switches and a proper control of the vapor-arc device excitation.

70 In instances in which the arc drop through the devices A and B is objectionable during steady state power supply to the load circuit, device shunting switches may be provided. In the system of Fig. 7, such switches are shown at 66 and 68 for devices A and B, respectively. Through the provision of suitable means (not shown) these shunting switches may be selectively closed

after each tap changing operation has been completed and maintained closed until the succeeding operation is to be instituted.

The system of Fig. 8 illustrates one manner in which a plurality of vapor-arc devices may be excited from but a single set of excitation transformers. In the system shown, the secondary winding of power transformer 10' is provided with taps 1, 2, 3, 4 and 5 intermediate each of which and the load circuit 12 is disposed a symmetrically-conducting vapor-arc device of the type already described. The make-alive elements 18 of each of the five vapor-arc devices A, B, C, D and E are excited from a transformer 22' while elements 19 of the devices derive their excitation from a transformer 26'. The primary winding 18 of transformer 26' is energized from the power source conductors 11 through a circuit which includes a control switch 72, while the primary winding 74 of transformer 22' is energized through a circuit which includes selector switches 75 to 79, inclusive, by the potential appearing across any one of the vapor arc devices.

The secondary windings 81 and 82 of exciting transformer 22' supply, through suitable selector switches, the inner make-alive elements 18 of the vapor arc devices, while the secondary windings 84 and 85 of transformer 26' similarly supply, through groups of selector switches, the outer make-alive elements 19 of the vapor arc devices A to E, inclusive.

In operation of the tap-changing system of Fig. 8, the control or selector switches are manipulated in the following manner. Assuming that the load circuit 12 is completely disconnected from transformer 10', the first step is to close switch 72 which places the equipment in condition for selective connection with any one of the taps 1 to 5, inclusive. To connect the load to tap 1, close switches 81. This operation causes transformer 26' to excite the other make-alive elements 19 of vapor arc device A to thereby render it conductive.

To shift the connection from tap 1 to tap 2 close switches 83 and 75. This sets up a circuit, influenced by the potential across device A, for the inner make-alive elements of device B. Next open switches 81 to render device A non-conductive and to thereby effect the excitation of the inner make-alive elements of device B. Device B is now conductive. To shift its excitation to the power source influenced circuits, close switches 80 which energizes the other make-alive elements of device B. Next, open switches 83 and 75 to disconnect the inner make-alive elements of device B.

In a similar manner, a shift of power circuit connection from tap 2 to tap 3 is effected by first closing switches 81 and 76, opening switches 80, closing switches 82 and opening switches 81 and 76.

To shift from tap 3 to tap 4, close switches 84 and 77, open switch 82, close switches 85 and open switches 84 and 77.

The remaining tap change in the voltage-raising direction, or from tap 4 to tap 5, is effected by closing switches 86 and 78, opening switches 85, closing switches 87 and opening switches 86 and 78.

Shifting of the tap connections in the opposite or voltage-lowering connection will be seen to be effected in a manner which is quite comparable to that just explained. For example, to shift from tap 5, in which the load current is carried by vapor-arc device C, to tap 4 in which the current

is carried by device D, switches 94 and 79 are first closed to set up a circuit for the inner-make-alive elements 18 of device D. Switches 91 are then opened to remove the excitation from the other make-alive elements of the device E to render it non-conductive. The increased voltage drop across the device being applied to the exciting transformer 22' effects the excitation of the inner make-alive elements of device D, thereby rendering it conductive. Switches 95 are now closed to effect the excitation of the outer elements of the device D and switches 94 and 79 are opened to remove the excitation from the inner elements of the conducting device.

15 As will be seen, to shift tap 4 to tap 3, switches 91 and 78 are closed, switches 95 are opened, switches 92 are closed and switches 91 and 78 are opened.

16 A shift from tap 3 to tap 2 is effected by closing switches 88 and 77, opening switches 92, closing switches 90 and opening switches 88 and 77.

17 Finally a shift from tap 2 back to tap 1 is effected by closing switches 98 and 76, opening switches 90, closing switches 87 and opening switches 98 and 76.

18 Disconnection of the load 12 from any one of the several taps may in the system of Fig. 8 be effected by opening the control switch 107. It will be apparent from the description of the system just completed that the number of tap controlling vapor arc devices which may be excited from a single pair of excitation transformers is not restricted to five but may be any number desired.

19 In the event that it is desired to apply vapor-arc devices to a tap changing system without utilizing the potential drop across one device to effect the excitation of the succeeding device in a tap changing operation, the combination shown in Fig. 9 may be employed. In Fig. 9 the load circuit 12 is energized from any one of a plurality of taps on the secondary winding of the power transformer 10" through circuits which include vapor arc devices A' to E', inclusive, intermediate which devices and the load is disposed a tap-bridging auto-transformer 100. It will be recognized that were devices A' to E' to be replaced by a conventional type of contactor switches, the system illustrated will be an exact reproduction of a well known type of single winding tap-changing scheme utilizing a tap-bridging auto-transformer. Hence, the vapor arc devices, which are illustrated as being provided with but a single pair of make-alive elements 19, function merely to interrupt and establish the load circuits in the same manner as would engageable contact type switches.

20 To supply excitation to the make-alive elements of the vapor-arc devices, a transformer 102, having four duplicate secondary windings 104 and a primary winding 105 energized from the power source circuit through a control switch 107, is provided. Intermediate the secondary windings of the transformer 102 and the make-alive elements of the several vapor arc devices is disposed a multi-pole control switch 106 in the manner illustrated. The several blades of this switch are arranged for gang operation, the switch being capable of nine separate positions indicated by 70 the pointer at the right of the diagram.

21 To place the system in operation, control switch 107 is first closed to energize exciting transformer 102. When switch 106 occupies position 1, as illustrated, only the make-alive elements of device A' will be excited and the load circuit 12 thus

will be supplied through device A' from tap 1. When switch 106 is moved to position 2, the make-alive elements of the device B' are also excited so that the load will then be supplied from the two adjacent transformer winding taps 1 and 3 through devices A' and B' which feed through opposite halves of auto-transformer winding 100. For such a condition the load circuit will be influenced by a voltage which corresponds to point 2 intermediate the taps 1 and 3.

22 Advancement of the control switch to position 3 removes the excitation from device A' and thus causes the load to be influenced by the voltage of tap 3. Advancement of the switch to position 4 effects the excitation of device B' thereby causing the load to be influenced by the voltage corresponding to the point 4. Further advancement to position 6 removes the excitation from device B' and raises the load circuit voltage to that of tap 5. In a similar manner further advancement of the control switch progressively raises the load circuit voltage to that of points 6, 7, 8 and 9 of the secondary winding of transformer 10", in which last-named position all of the winding is connected to the load circuit 12 through the device E'.

23 As will be apparent, a progressive movement of the control switch 106 in the opposite direction causes the load circuit to be influenced by the voltages corresponding to the points 8, 7, 6, 5, 4, 30 3, 2 of the winding and lastly by that of tap 1.

24 To effect a complete disconnection of the load circuit from all of the power transformer taps, regardless of the position of selector control switch 106, it is only necessary to open master control switch 107. Connection of the load circuit with the power transformer may be established, as has been pointed out, by the mere closure of switch 107.

25 Although I have shown and described certain specific embodiments of my invention, I am fully aware that many modifications thereof are possible. My invention, therefore, is not to be restricted except insofar as is necessitated by the prior art and by the scope of the appended claims. 45

I claim as my invention:

1. The combination with an electrical winding having a plurality of taps, a circuit disposed for connection therewith, and a source of alternating-current voltage disposed to circulate current through said winding and circuit, of a vapor-arc device, which is capable of conduction when excited, disposed intermediate the circuit and each of the winding taps, means for selectively exciting each of said devices from said alternating-current voltage, and means for additionally exciting each of said devices from a characteristic of any one of said remaining devices when non-conductive. 55

2. The combination with an electrical winding having a plurality of taps, a circuit disposed for connection therewith, and a source of alternating-current voltage disposed to circulate current through said winding and circuit, of a pair of vapor-arc devices each of which is capable of conduction when excited, means for disposing one of said devices intermediate the circuit and one of the winding taps and the other device intermediate the circuit and another of said taps, means for exciting each of said devices from said alternating-current voltage, and means for additionally exciting either of said devices from a characteristic of the other device when non-conductive. 65

3. The combination, with a transformer wind- 75

- ing having a plurality of taps, a circuit disposed for connection therewith, and a source of alternating-current voltage disposed to circulate current through said winding and circuit, of a vapor-
5 arc device, which is normally non-conductive and capable of full-wave conduction when excited, disposed intermediate the circuit and each of the winding taps, means for selectively exciting each of said devices from said alternating-current
10 voltage, and means for additionally exciting each of said devices from the voltage appearing across any one of said remaining devices when non-conductive.
4. The combination, with a transformer winding having a plurality of taps, a circuit disposed for connection therewith, and a source of alternating-current voltage disposed to circulate current through said winding and circuit, of a vapor-
15 arc device, which is normally non-conductive and capable of full-wave conduction when excited, disposed intermediate the circuit and each of the winding taps, means for exciting from said alternating-current voltage any one of said devices to the winding tap associated with which it is desired that a circuit connection be established, and means for connecting for excitation by the voltage appearing across said first-named device when rendered non-conductive any other of said devices to the winding tap associated with which it is desired that the circuit connection be shifted upon a removal of excitation from said first-named device.
5. In a transformer tap-changing system disposed to shift the connection of an electrical circuit from one to another of the taps of a multi-tap transformer winding, said system comprising a vapor-arc device, normally non-conductive and capable of full-wave conduction when excited, disposed intermediate the circuit and each of the winding taps and means for exciting each of said devices from the transformer voltage and also from the potential appearing across any one of the remaining devices when non-conductive, the method of effecting a change of circuit connection from a tap associated with a device maintained conductive by transformer-voltage excitation to any other tap without interruption of circuit current which comprises connecting the exciting means of the device associated with that other tap across the first-named device, discontinuing the excitation of said first-named device to render it non-conductive which allows its potential to build up sufficiently to effect excitation of said second-named device, influencing the exciting means of the second-named device by the transformer voltage, and disconnecting the exciting means of this device from the first-named device.
6. In a transformer tap-changing system disposed to shift the connection of an electrical circuit from one to another of the taps of a multi-tap transformer winding, said system comprising a vapor-arc device, normally non-conductive and capable of full-wave conduction when excited, disposed intermediate the circuit and each of the winding taps and means for exciting each of said devices from the transformer voltage and also from a characteristic of any one of the remaining devices when non-conductive, the method of effecting a change of circuit connection from a tap associated with a device maintained conductive by transformer-voltage excitation to any other tap without interruption of circuit current which comprises connecting the exciting means of the device associated with that other tap to

the first-named device, discontinuing the excitation of said first-named device to render it non-conductive which allows its said characteristic to effect excitation of said second-named device, influencing the exciting means of the second-named device by the transformer voltage, and disconnecting the exciting means of this device from the first-named device. 5

7. In combination with a source of alternating-current power, a transformer having a winding provided with a plurality of taps, and a circuit disposed to be energized by said power source through a connection which includes one of the winding taps, means for shifting said connection from one to another of said taps without circuit-current interruption comprising two electronic devices, each of which is capable of full-wave conduction when excited, disposed intermediate the circuit and the winding, tap-selector switches disposed intermediate one of said devices and the odd-numbered winding taps, tap-selector switches disposed intermediate the other of said devices and the even-numbered winding taps, means for selectively exciting each of said electronic devices from the voltage of said alternating current source, and means for additionally exciting either of said devices from a characteristic of the other device when non-conductive. 10 15 20 25

8. In a transformer-tap changing system disposed to shift the connection of an electrical circuit from one to another of the taps of a multi-tap transformer winding without circuit-current interruption, the combination of two vapor-arc devices, each of which is capable of full-wave conduction when excited, disposed intermediate the circuit and the winding, tap-selector switches disposed intermediate one of said devices and the odd-numbered winding taps, tap-selector switches disposed intermediate the other of said devices and the even-numbered winding taps, means for selectively exciting each of said electronic devices from the voltage of said alternating-current source, and means for additionally exciting either of said devices from a characteristic of the other device when non-conductive. 30 35 40 45

9. In combination with a transformer tap-changing system adapted to operate in a load-carrying circuit comprising a controllable electronic conduction device, a circuit breaker disposed to shunt said device for the purpose of eliminating the arc drop therethrough when the system is not being operated. 50

10. In combination, a transformer tap-changing system adapted to operate in a load-carrying circuit comprising a plurality of controllable vapor-arc conduction devices through which the transformer circuit is selectively completed, and a circuit breaker disposed to shunt each of said devices for the purpose of eliminating from the transformer circuit the arc drop of the device when no tap changing operation is being effected. 55 60

11. In a transformer tap-changing system adapted to operate in a load-carrying circuit, the combination of a plurality of vapor-arc devices each comprising two main electrodes of vaporizable reconstructing material and a make-alive element associated with each electrode for forming a cathode spot thereon, and means for selectively exciting the make-alive element of said devices, each element of the excited device being acted upon during alternate half cycles of transformer voltage in a manner to render the device a full-wave conductor. 65 70

12. In a transformer tap-changing system 75

adapted to operate in a load-carrying circuit, the combination of a plurality of pairs of asymmetrically conducting vapor-arc devices, each of said devices having a make-alive element, the devices in each pair being interconnected to be capable of symmetrical conduction, and means for selectively exciting the make-alive elements of the several pairs of devices.

13. In a transformer tap-changing system adapted to operate in a load-carrying circuit, the combination of a plurality of controllable conducting means each comprising a pair of vapor-arc devices each of which has an anode element,

a cathode element of vaporizable reconstructing material, and a make-alive element associated with each cathode, means for connecting the anode element of each device with the cathode element of the other device, and means for selectively exciting the make-alive elements of the several pairs of devices, each make-alive element of the excited pair being acted upon during alternate half cycles of transformer voltage in a manner to render the said pair of devices so interconnected a full-wave conductor. 5
